UNITED STATES PATENT OFFICE

JOHANNES TÜRKE, OF BEUTHEN, GERMANY, ASSIGNOR TO EMIL KLEINSCHMIDT,
OF FRANKFORT-ON-THE-MAIN, GERMANY

APPARATUS FOR BINDING PULVERULENT FUEL

Application filed May 24, 1928; Serial No. 280,341, and in Germany August 9, 1926.

My invention relates to means for binding pulverulent fuel prior to briquetting same, in which a liquid binder, for instance liquid pitch, is mixed with the fuel by spraying. 5 It has already been proposed to atomize the binder and to admix it to the fuel material through the medium of a nozzle operated by steam or air under pressure, the binder being ejected into the freely flowing material. 10 In the process as heretofore performed, however, the binder is not supplied to the nozzle under pressure, and this involves several drawbacks: The binder has a tendency to stick to the mouth of the nozzle so that frequent inspection of the nozzle is required, 15 atomizing by steam has the additional drawback that a considerable percentage of water is admixed to the material, causing an increased consumption of binder. On the other hand, atomization by air under pressure while eliminating the drawback of increased consumption of binder, involves the formation of dust which is so excessive that it must be abated by admixing steam in most cases, 20 thereby requiring steam in addition to the already considerable volume of compressed air required. Apart from this the loss of the very fine dust is considerable and therefore the process of atomizing with compressed air 25 is not commercial.

These drawbacks are overcome according to this invention by supplying the liquid binder to the nozzle under a predetermined preferably constant pressure.

35 In reducing the invention to practice I prefer providing a supply tank from which the binder, for instance fluid pitch, is forced into a pressure tank in which its pressure is regulated exactly to a predetermined amount by 40 means of suitable means, for instance a relief valve. Preferably the pressure in the tank is 90 to 150 lbs. per sq. in. Under this pressure the binder is supplied to a nozzle, preferably a spray nozzle, or a set of nozzles, 45 which may be operated alternately or in any combination, as desired.

In this manner, with the binder under high pressure, the atomization in the spray nozzle is extremely fine. Sticking of the binder to 50 the nozzle and consequent reduction of its

area are prevented by the high pressure acting on the binder and by the elimination of carriers such as compressed air or steam which by cooling the nozzle increase the tendency of the binder to stick.

55 In the drawing affixed to this specification and forming part thereof an apparatus in which the process may be performed, is illustrated diagrammatically by way of example.

In the drawing *a* is a tank for the fluid binder such as pitch or the like, *b* is a pump the suction pipe *h* of which is connected with the tank *a* and which delivers to a pressure tank *c* through a delivery pipe *h'*. *f* is a relief valve on the pump, *g* is a by-pass connecting the relief valve *f* with the suction pipe *h*, *d* is a relief valve on the tank *c* which is connected with a return pipe *e* to the tank *a*, the relief valve *d* regulating the pressure in the air or gas space of the 60 tank to a predetermined amount, *c'* is a pressure gauge connected with the air or gas space, *i* is a discharge pipe connected with the liquid space of the tank, *k* is a nozzle, preferably a spray nozzle, *m* is a rotary mixing cylinder and *n* is a hopper from which the pulverulent fuel *o* flows into the cylinder *m* so as to be intersected by the jet of the nozzle *k*. If desired an auxiliary nozzle *k'* 65 may be provided for the purpose specified. 70

75 In the operation of this apparatus the pump *b* forces the binder from the storage tank *a* into the pressure tank *c*, the pressure in which is maintained constant by the relief valve *d*. On one of the nozzles *h* being opened 80 a spray of liquid binder under constant pressure, but undiluted by air or steam, is directed onto the stream of pulverulent fuel issuing from the hopper *n*, the mixture of fuel and binder being mixed further in the 85 revolving cylinder *m*.

I wish it to be understood that I do not desire to be limited to the exact details of construction shown and described for obvious modifications will occur to a person 90 skilled in the art.

I claim:

Apparatus for applying liquid binder to pulverulent fuel comprising a supply tank for the liquid binder, a pump, a conduit connect- 100

ing the tank and pump, a by-pass between the pump and conduit, a relief valve controlling said by-pass, a pressure tank, a supply connection between the pump and pressure tank, a return pipe connecting the pressure tank and supply tank, a relief valve controlling said return pipe, a spray nozzle in connection with said pressure tank, and means for directing an exposed flow of the pulverulent fuel into the spray issuing from said nozzle.

5 In testimony whereof I affix my signature.

JOHANNES TÜRKE.
